UNITED STATES PATENT OFFICE.

CHARLES W. HEERGEIST, OF OAK LANE, PENNSYLVANIA, ASSIGNOR TO MATHER MANUFACTURING CO., OF PHILADELPHIA, PENNSYLVANIA.

DESIGN FOR A FONT OF PRINTING-TYPE.

SPECIFICATION forming part of Design No. 29,272, dated August 23, 1898.

Application filed July 30, 1898. Serial No. 687,368. Term of patent 7 years.

To all whom it may concern:

Be it known that I, CHARLES W. HEERGEIST, a citizen of the United States, residing at Oak Lane, in the county of Philadelphia and State of Pennsylvania, have invented and produced a certain new and original Design for a Font of Printing-Type, of which the following is a full, clear, and exact description.

My design relates more especially to display-type; and it consists, specifically, in giving to the kerns and serifs a peculiar conformation, essentially as shown in the accompanying drawing, which forms a part hereof.

In the said drawing I have shown a font of type comprising upper-case letters, the sign &, the English pound (money) mark, certain diphthongs, the dollar sign, and the numerals, the lower-case letters, and the points, the same being the usual characters which go to make up a font of type.

As shown in the drawing, the leading or material features of my design consist in extending the kerns of such letters as A, M, N, R, and X below the line and in providing peculiarly-pointed serifs on the letters A, C, E, F, G, J, K, L, M, N, R, S, T, U, V, W, X, Y, and Z, and on other characters, as shown, the said serifs having a certain obliquity with reference to the body of the characters. In the lower-case and in some of the points this obliquity is present.

What I claim is—

The design for a font of printing-type, substantially as shown and described.

In testimony whereof I have hereunto set my hand this 29th day of July, A. D. 1898.

CHARLES W. HEERGEIST.

Witnesses:

W. J. MCKEE,

WILLIAM C. STOEVER.
